UNITED STATES PATENT OFFICE

114,210

DESIGN FOR A COMBINED KEYHOLE LIGHTER AND KEY RING

Irving Florman, New York, N. Y.

Application August 3, 1938, Serial No. 79,078

Term of patent 14 years

To all whom it may concern:

Be it known that I, Irving Florman, a citizen of the United States, residing at New York, in the county of New York and State of New York, have invented a new, original, and ornamental Design for a Combined Keyhole Lighter and Key Ring, of which the following is a specification, reference being had to the accompanying drawing, forming a part thereof.

The figure is a perspective view of a combined

keyhole lighter and key ring embodying my new invention.

The characteristic features of my design reside in the combination of the closed, horse-shoe figure and the keyhole lighter as shown.

I claim:

The ornamental design for a combined keyhole lighter and key ring, substantially as shown and described.

IRVING FLORMAN.
